UNITED STATES PATENT OFFICE

2,620,695

VISE HAVING DISPLACEABLE SCREW SEGMENT FOR QUICK ADJUSTMENT

Jack F. Eierman, Milwaukee, Wis., assignor to Mechem Engineering, Inc., Milwaukee, Wis.

Application March 14, 1951, Serial No. 215,568

3 Claims. (Cl. 81—36)

1

My invention relates to vises, and more particularly to quick-opening vises.

The object of my invention is to provide a vise in which the movable jaw may be easily engaged and disengaged in its relation to the clamping screw, at any predetermined point along the length of the screw.

Another object of my invention is to provide a quick-opening vise which may be manipulated and adjusted in the conventional manner.

Still another object of my invention is to provide a device of the character described that may be constructed to accommodate material of varied dimensions being worked on.

A further object of my invention is to provide a vise that will position its working and moving parts in a manner to place them ready for use without reversing the movement of the screw.

A still further object of my invention is to provide a quick-opening vise that is simple in construction, has but few moving parts, and is easy to manipulate by the operator without mechanical skill.

It is manifest to anyone familiar with wood working or the like, that the work piece, to be retained in position in the vise while the various operations are performed thereon, may be of varied widths and dimensions. It is imperative that a vise for clamping the work piece should be quickly adjusted. This is also true when production demands quick placing and removing of the work piece in the vise.

In the device claimed, specified and illustrated, the clamping jaw is quickly released, and the sleeve is brought to its original position by a revolving adjustment of the screw with less than a complete revolution thereof.

Other and further objects of my invention will become more apparent as the description proceeds when taken in conjunction with the drawing in which:

Figure 1 is a side view of the assembled device.

Figure 2 is a longitudinal cross-section of the device as shown in Figure 1.

Figure 3 is a lateral cross-sectional view of the screw, sleeve and housing, taken at the line 3—3 in Figure 2, showing the insert member in engagement with the threaded housing, and

Figure 4 is a similar view as shown in Figure 3 with the insert member disengaged on the threaded housing.

Similar characters of reference indicate corresponding parts throughout the several views, the character 10 designating a vise body, which may be attached to a work bench or the like (not shown), by means of screws or bolts disposed through apertures 11 on outwardly projecting members 12, on both sides thereof.

The body 10 has a pair of longitudinally ex-

2

tending tubular guides 13 extending therethrough, which act as slidable supports for a pair of longitudinal rods 14 attached at 15 to a movable jaw member 16, which jaw, obviously, is of a size and contour to correspond with a stationary jaw 17 forming an integral part of the body 10. The jaws 16 and 17 may be of any shape or contour, and act as supporting means for clamping a work piece (not shown) while work is being performed thereon.

There is a threaded housing 18 inserted longitudinally into the body 10. This housing 18 is threaded at 19 on its inner face. This type of construction, of course, may be varied. The body itself may be threaded, instead of having an insert with a thread on its inner bore. A longitudinally threaded screw 20 is rotatably suspended centrally within the inner threaded opening of the housing 18 by means of an aperture 21 in the jaw 16 at its forward end, and an aperture in a flange shown as 22 attached to the body 10 by means of screws 23 at the rearward end thereof. Disposed between the flange 22 and a rear face 24 of the body 10 is shown a washer 25, which has an aperture therethrough of a greater diameter than the screw 20. This washer is also supported by the screws 23 which attach the flange 22 to the body 10 of the device.

A cylindrical sleeve member 26 slidably engages the threaded screw 20 within the threaded housing. The longitudinal screw 20 is provided with a flat surface 27 along its entire length, while a pin shown as 28 extends through the wall of the sleeve 26 in alignment with the flat surface 27 to limit the radial movement of the screw 20 within the sleeve 26.

The sleeve member 26 is also provided with an elongated slot shown as 29 through its side wall. This slot is of a size and dimension to receive a segmental insert 30 threaded at its outer face 31, to fit the threads 19 on the housing 18, and on its inner face 32 having threads to fit the threads on the outer face of the longitudinal screw 20.

The forward end of the screw 20 is provided with a head member 33, having an aperture extending laterally therethrough to slidably support a lever 34, which extends therethrough and which is equipped with the conventional limit stop knobs shown at 35 on each of its ends, so that the lever 34 may be moved slidably to either one side or the other, to provide the necessary leverage when manipulating the screw, thereby actuating the movable jaw 16.

A resilient member in the form of a spring 36 encircles the longitudinal screw 20, and enters the aperture in the washer 25 for engagement with the inner face of the flange 22 on the one end, and the face 37 of the sleeve 26 on the other end.

In operation, the device functions as follows: The screw 20 is revolved by means of the lever 34 into position shown in Figure 4 which permits the operator to move the jaw 16 outward so that the work piece may be inserted between the jaws 16 and 17, at which time the operator moves the jaw 24 inward and revolves the screw 20 into the position as shown in Figure 3 which brings the segmental insert 30 into threaded engagement with the thread on the screw 20 and the inner thread 19 of the housing 18, and as the screw 20 is revolved, the movable jaw 16 is forced toward the stationary jaw 17 for securely clamping the work piece between the jaw 16 and 17. When the work piece is to be released, it is merely necessary for the operator to revolve the screw 20 in the opposite direction, to the position shown in Figure 4, at which time the segmental insert 30 is brought out of engagement with the screw 20 in the inner thread 19 of the housing 18 thereby permitting the jaw 16 to be pulled outward to release the work piece. The flat portion 27 on the screw 20 is brought into engagement at one point with the insert 30, as the pin 28 limits the movement of the screw 20 within the sleeve 26, and the sleeve 26 is urged forward to its original position by means of the resilient member 36.

In the chosen embodiments of my invention, there are many features that identify the instant invention from the prior art. However, I am fully cognizant of the fact that in the arrangement of the component parts constituting the device, many changes may be made that will not affect their efficiency or operativeness, and without departing from the spirit of my invention or the scope of the appended claims.

Having thus described my invention, what I claim and desire to secure by Letters Patent in the United States is:

1. In a vise, the combination of a body having a stationary jaw, a movable jaw slidably supported by said body, said body provided with a threaded bore extending longitudinally therethrough, a threaded screw centrally disposed through the bore in said body, said screw rotatably supported at its forward end by said movable jaw, and at its rearward end by said body, a longitudinal sleeve slidably engaging said screw, said sleeve having an outer diameter less than the threaded bore in said body, said sleeve provided with an elongated aperture through its side wall, said threaded screw having a flat surface along its entire length, a stop member disposed through the side wall of said sleeve adjacent the flat surface of said screw, and extending inward therefrom, said stop member employed to limit the radial movement of said threaded screw within said sleeve, and a segmental insert slidably disposed within said elongated aperture in said sleeve, said insert provided with an outer threaded surface for engaging the longitudinal threaded bore within said body, and an inner thread for engagement with the thread on said screw and slidably actuated by the revolution of said screw within said sleeve which radial movement is governed by the stop member within said sleeve.

2. A quick-opening vise comprising, an internally threaded body provided with a stationary jaw, a movable jaw, means for slidably guiding said movable jaw within said body portion, a threaded screw member longitudinally and centrally disposed within said body, said screw provided with a flat surface extending longitudinally.

along its entire length, means for rotatably mounting said screw onto said movable jaw on one end, and on said body on its other end, a cylindrical sleeve slidably engaging said screw, 5 said sleeve having a diameter less than the inner threaded portion of said body, said sleeve having a longitudinal aperture extending through its wall, a pin member extending through the wall of said sleeve for engagement with the flat portion of said screw to limit the radial movement of said screw within said sleeve, a segmental insert member slidably mounted within the elongated aperture in said sleeve member, said insert member having a threaded outer surface 10 for engagement with the inner threaded surface of said body and a threaded inner surface for engagement with the threaded screw member, means on one end of said screw member adjacent said movable jaw for rotating said screw within said sleeve, thereby bringing said insert member into engagement with the internal threaded surface of said body due to the engagement of one side of said flat surface of said screw with said pin, thereby causing said sleeve to revolve in threaded engagement with said body for moving said adjustable jaw toward and away from said stationary jaw.

3. A quick-opening vise of the character described comprising, an internally threaded body provided with a stationary jaw, a screw member centrally disposed within the internal thread of said body, said screw member being of a smaller diameter than said internal thread in said body and having a longitudinal flat surface thereon, a movable jaw attached to one end of said screw member, said movable jaw slidably supported by said body, said screw member supported at one end by said movable jaw and on the other end by said body member, a cylindrical sleeve member 30 slidably engaging said screw member and having a stop member disposed through its walls for engagement with the flat surface of said screw, said sleeve being of a diameter smaller than the internal threaded surface of said body and having a longitudinal slot through its side, an insert slidably mounted within said slot, said insert threaded at its inner and outer face, means for revolving said screw member thereby raising said insert out of said sleeve into engagement with the inner thread of said body and the outer thread of said screw due to one side of said flat surface contacting said segment, and a resilient means disposed between the one support for said screw and the one end of said sleeve to return said sleeve to its original position when said sleeve is released from said screw due to the flat surface of said screw member disengaging from said stop member when said screw is revolved in an opposite direction.
